UNITED STATES PATENT OFFICE

163,315

FABRIC DISPLAY RACK

Russell B. Newton, Danville, Va., assignor to Dan
River Mills, Incorporated, a corporation of
Virginia

Application June 6, 1950, Serial No. 10,383

Term of patent 14 years

(Cl. D80—9)

To all whom it may concern:

Be it known that I, Russell B. Newton, a citizen of the United States, residing at Danville, in the county of Pittsylvania and State of Virginia, have invented a new, original, and ornamental Design for a Fabric Display Rack, of which the following is a specification, reference being had to the accompanying drawing, forming part thereof, in which:

Figure 1 is a side perspective view of a fabric display rack, showing my new design.

Figure 2 is a perspective view of the rack shown in Figure 1 having bolts of cloth arranged thereon. The dominant features of my design reside in the portions shown in full lines, and the dotted lines showing of the bolts of cloth are for illustration only.

I claim:

The ornamental design for a fabric display rack, substantially as shown and described.

RUSSELL B. NEWTON.
